UNITED STATES PATENT OFFICE

2,573,547

AMALGAM CARRIER

Walter S. Crowell, Melrose Park, Pa., assignor to
The S. S. White Dental Manufacturing Company, a corporation of Pennsylvania

Application April 10, 1946, Serial No. 660,923

1 Claim. (Cl. 32—60)

1

My invention relates to that class of dental implements that are generally known as amalgam carriers and are particularly adapted to insert amalgam or other filling material into a tooth cavity to form a stopping therefor, and is especially directed to the means of connecting the plunger with the operating rod.

It has heretofore been proposed to construct amalgam carriers with the plunger and rod variously connected by a helically coiled wire or by a normally straight strand of wire forced to bend in the curved barrel of said carrier, which construction has proven to be unsatisfactory for the purpose intended.

The principal objects of my invention are to provide an amalgam carrier having its barrel curved to direct its forward nozzle at a conveniently directed angle to the axis of its handle, and having its plunger and rod mounted to reciprocate in the bore of said barrel and connected by a section of flexible shafting whose outer diameter is substantially less than the diameter of the barrel bore.

Other objects of my invention are to provide an amalgam carrier having its plunger and operating rod connected by a section of flexible shafting comprising a plurality of oppositely coiled helical layers of wires wound about a single strand of core wire.

Further objects of my invention are to provide an amalgam carrier with a removable and replaceable terminal tip through which the snugly fitted plunger is arranged to slide.

My invention also includes the novel arrangement of construction in which the finger-hold collar connects the separately formed barrel and tubular handle and in which the plunger retracting spring, which embraces the operating rod, is enclosed to exert pressure tending to force the thumb trigger button rearwardly, and effecting the consequent withdrawal of the plunger in the nozzle.

Specifically stated, the form of my invention as hereinafter more definitely described comprises an amalgam carrier having a tubular handle terminating forwardly in a collar serving as a finger-hold and which forms the mounting for the forwardly extending barrel which carries the plunger in its laterally deflected terminal region. Said handle is provided with a ferrule serving as a buffer for the adjusting nut which is adjustable on the reciprocating operating rod to vary the axial position of the plunger in the terminal nozzle and which is forced into engagement with said ferrule by the spring in the handle

2

when the thumb trigger button is released to effect withdrawal of said plunger.

My invention also includes all of the various novel features of construction and arrangement 5 as hereinafter more definitely specified.

In the accompanying drawings, Figure 1 is a side elevational view of an amalgam carrier conveniently embodying my invention; Fig. 2 is a central vertical longitudinal sectional view of the amalgam carrier shown in Fig. 1, on a greatly enlarged scale showing the relatively associated parts in their normal position; Fig. 3 is a central vertical longitudinal sectional view similar to Fig. 2 but showing the movable parts shifted to 10 the forward limit of their movement; Fig. 4 is a transverse vertical sectional view taken on the line 4—4 in Fig. 2 on a much greater enlarged scale; Fig. 5 is a transverse vertical sectional view taken on the line 5—5 in Fig. 3 on the same scale as Fig. 4; and Fig. 6 is a fragmentary side elevational view of the flexible coupling shaft and plunger.

In said figures, the tubular handle 1 terminates forwardly in the collar 2 which carries the forwardly extending barrel 3 having its forward portion 4 curvilinearly deflected downwardly and terminating in the removable and replaceable nozzle 5, which is removably engaged therewith by the screw threads 6.

Said handle 1 terminates rearwardly in a buffer ferrule 7 which is engaged therewith by the screw threads 8 and which has the peripheral knurling 9 by which it may be readily rotated, and the bore 10 through which the stem 11 of the thumb trigger button 12 slidably extends.

The forward region of the thumb trigger button stem 11 is conveniently provided with the screw threaded bore 13 into which the screw threaded rearward terminal region of the axially reciprocating operating rod 14 is extended in threaded engagement therewith for axial adjustment.

Within the handle 1 and screw-threaded embracing the rod 14 is the adjustable lock nut 15 between which and the collar 2 is disposed the plunger retracting spring 16 which is helically coiled about the rod 14 within the bore of said handle 1, and which is arranged to be compressed by the forward movement of the thumb trigger button 12, as illustrated in Fig. 3, and which normally tends to force the adjusting nut 15 into engagement with the buffer ferrule 7, as illustrated in Fig. 2.

The forward end portion of the rod 14 is flexible and includes a length of flexible shafting 17 of relatively reduced diameter extended through

the curved region 4 of the barrel 3, and formed integral with the non-flexible portion of the rod 14 and the plunger 18 and flexibly connects them together in a relatively definite axial relation.

The flexible shaft section 17 of the operating rod 14 comprises an axial core wire 19 and the coiled layers 20, 21 and 22 of wire alternately laid in relatively opposite directions, as best shown in Fig. 6.

My invention is advantageous in that it provides a positive action of the plunger 18 by reason of its connection with the operating rod 14 by the flexible shaft section 17 having the core wire 19 which maintains a definite axial length between the rod 14 and plunger 18 and the outer coils of said flexible shaft section provide a plurality of rounded surfaces serving as restricted bearings slidable upon the inner surface of the bore of the curved forward portion 4 of the barrel 3. Furthermore, the thumb trigger button 12 is conveniently adjustable with respect to the plunger 18 so that the amalgam receiving chamber 23 in the nozzle forward of the plunger may be varied to measure the volume of amalgam as desired.

I do not desire to limit my invention to the precise details of construction and arrangement as herein set forth, as it is obvious that various modifications may be made therein without de-

parting from the essential features of my invention as defined in the appended claim.

Having thus described my invention, I claim:

An implement of the class described, comprising a hollow handle having a forwardly extended barrel curvedly deflected laterally and terminating in a nozzle region, a plunger mounted for axial movement in said nozzle region, trigger means including a stem and rod adjustably engaged in threaded relation and arranged to force said plunger outwardly, a lock-nut arranged to retain said stem and rod in axially adjusted relation, a section of flexible shafting including an axial core wire, connecting said rod and plunger, and a spring contained in said handle and tending to withdraw said plunger into said nozzle region.
